UNITED STATES PATENT OFFICE.

WILLIAM L. HURD, OF EATON RAPIDS, MICHIGAN.

WATER AND AIR ATTACHMENT FOR INLET-MANIFOLDS.

1,179,926.

Specification of Letters Patent. Patented Apr. 18, 1916.

Application filed August 25, 1914. Serial No. 858,446.

To all whom it may concern:

Be it known that I, WILLIAM L. HURD, a citizen of the United States, residing at Eaton Rapids, in the county of Eaton and State of Michigan, have invented certain new and useful Improvements in Water and Air Attachments for Inlet-Manifolds, of which the following is a specification.

The invention has for an object to provide desirable means for introducing auxiliary constituents into the charges for internal combustion engines, and seeks particularly to present a simple attachment suitable for use upon any ordinary engine already constructed without modifying the structural details or mode of operation.

An important aim is to give a desirable mechanism for admitting water to the intake manifold of internal combustion engines.

A further important object is to make available a desirable and efficient means for controlling and modulating auxiliary air and water feeding devices.

Additional objects and advantages will be apparent from the construction, arrangement, and combination of parts hereinafter set forth, and shown in the drawings, in which,—

Figure 1 illustrates my invention installed upon a motor vehicle of ordinary type, Fig. 2 is a detail edge view of the device with part of the cover removed, Fig. 3 is a sectional view in the major medial plane of the device.

There is illustrated an intake manifold 10 upon which there is secured a body casting 11 of a suitable material in which there are formed two vertical parallel bores 12 and 13, smoothly finished and terminating in conical seats 14, opening through the centers of which there are passages 15 and 16 respectively. The passage 15 opens through the lower end of the casting and suitable connections 17 are provided leading to the manifold 10 therefrom. The passage 16 opens through the side of the block, and water supply connections 18 are provided therefor. Immediately above the seats 14 a horizontal passage 19 is formed in the casting intersecting the bores 12 and 13 and having an air inlet valve 20 at its outer end. A valve 21 is also provided upon the water supply 18, as shown. Snugly fitted in the bores 12 and 13 there are needle valve devices 22 and 23, each of similar form and

comprising a cylindrical body portion having a multiplicity of circumferential parallel oil grooves 24, the lower end being reduced for a distance as at 25 and terminating in a conical portion 26 with a more gradually tapered portion 27 adapted to project into the passage 15 or 16 as the case may be. Pivot ears 28 are formed at the upper ends of the valve members 22 and 23, upon which there are pivoted respective links 29 and 30. Carried upon the member 11 there is a cover or casing 31, in which there are carried sleeves 32, threaded in suitable openings in the top of the casing, the sleeves being alined respectively with the bores 12 and 13 and being secured adjustably by lock nuts 33. Slidably engaged in these sleeves there are headed pins 34, with their heads presented downwardly and borne against the upper ends of the links 29 and 30 by springs 35. Pivoted upon suitable lugs 36 on the body 11 at one side of the casing 31 there are two bell crank levers 37 and 38, connected respectively to the upper ends of the links 29 and 30 at the extremity of one arm, while the other arm of each extends upwardly through a suitable slot 39 in the top of the casing.

The body 11, for convenience in manufacture and facility in installation, as well as to adapt the device most readily to the space available in the average motor vehicle hood, is formed of a rectangular block of brass or other soft metal of a non-corrosive nature having a thickness but little greater than the diameter of the bores 12 and 13 in one direction. The body is arranged on the manifold with one of its broader sides toward the engine, and the casing 31 conforms to the shape of the upper edge of the block so that the device does not project far and will not constitute a serious obstruction. The levers 37 and 38 are pivoted adjacent the rear edge of the block, and their lower arms extend on opposite sides of the links, the one stopping short immediately adjacent the link 29, to which it is pivotally connected, the other being pivotally connected to the link 30. On the foot board 39 there is pivoted a pedal 40 to which links 41 are slidably connected, pivotally connected to the respective levers 37 and 38. The rear ends of these levers are threaded and have engaged thereon adjusting nuts 41, against which the pedal strikes under foot pressure to draw upon the links, these nuts being se-

cured by lock nuts 42. The adjusting nuts are arranged so that a certain amount of movement of the valve 22 will occur under pressure on the pedal before the valve 23 is operated, although this arrangement is not arbitrary and may be varied as desired.

The advantages of an auxiliary air supply upon the intake manifold and of introducing moisture into the fuel mixture are well understood and will not require detailed presentation. It is important to note that by the device herein presented it is possible to supply auxiliary air without admitting water, if desired, and the device may also be adjusted to be operable to admit air, or air and water, at will, governed by the degree of movement of the foot pedal.

A liberal quantity of oil may be maintained in the casing 31, so that the valves 22 and 23 will be well lubricated and an oil seal formed therearound. The air inlet duct 19 may be connected in any desired way with a hot air pipe, not shown, and the water supply for the connections 18 may be either a small receptacle attached to the side of the motor, or the usual radiator with which connections may be made as at 43, preferably near the upper part in order that warm water may be assured, although the device will operate well with cold water.

In use, the engine is started and operated in the customary manner, and the auxiliary air and water supply controlled by the operator's foot, in accordance with the need. If desired any suitable familiar detent may be provided to hold the pedal releasably at various points in its movement.

It should be noted that by the arrangement of the valves and passages a double valve seal is formed between the water supply and the manifold, guarding well against casual inlet of water when not desired. The arrangement also insures the regularity of the water feed, the feeding of water to the air inlet passage 19, causing it to be carried immediately in small particles through the passage 15, to the manifold, where it is projected in a fine spray. This arrangement obviates the liability of irregular feeding of the water, and insures an even supply and mixture.

What is claimed:

1. A device of the class described comprising a body member having two vertical bores opening on its upper side and having terminal valve seats and ducts leading

therefrom, an intersecting passage formed in the body for the purpose described, cylindrical members snugly slidable in the bores, and having reduced lower end portions, their intermediate portions having a plurality of circumferential grooves, oil containing means at the upper side of the body, yieldable means engaged with the valves to hold them seated, and means to raise the valves.

2. In an internal combustion engine an inlet duct therefor, a body member having two vertical bores opening on its upper side and having terminal valve seats and ducts leading therefrom, duct connections being formed between the bores adjacent the seats, an air inlet passage being formed in communication with one, water supply connections with the terminal duct of the said one and inlet duct connections with the terminal duct of the other bore, valves slidable in the bores to close respective terminal ducts, and means to operate the valves with differential movement.

3. A body member having two vertical bores opening on its upper side, water supply and delivery ducts leading therefrom respectively, respective valves therein to close said ducts, an air inlet passage formed in the body intersecting the bores, valve members slidable in the bores including snugly fitted portions, links pivotally connected thereto and projecting upwardly, bell cranks carried pivotally by the body member each having one arm connected to a respective link, a removable cover for the body member, spring-pressed members carried thereby arranged in alinement with the links respectively and operative connections for said levers.

4. A body member having two vertical bores opening on its upper side, water supply and delivery ducts leading therefrom respectively, respective valves therein to close the ducts, an air inlet passage formed in the body intersecting the bores, valve members slidable in the bores, a pedal member, and extensible operative connections between the pedal and the valves.

In testimony whereof I affix my signature in presence of two witnesses.

WILLIAM L. HURD.
